(57) **CLAIM**

The ornamental design for a pet wearable extending band as shown and described.

DESCRIPTION

FIG. 1 is a top perspective view of a pet wearable extending band, showing our new design;

FIG. 2 is a top plan view thereof;

FIG. 3 is a bottom plan view thereof;

FIG. 4 is a left-side plan view thereof;

FIG. 5 is a right-side plan view thereof;

FIG. 6 is a front plan view thereof; and,

FIG. 7 is a rear plan view thereof.

The short dash-dash broken line features in FIGS. 1-3 illustrate stitching that forms no part of the claimed design.
